UNITED STATES PATENT OFFICE.

PHILIP E. BLUM, OF DANSVILLE, NEW YORK.

DESIGN FOR A SHOE.

51,042.

Specification for Design. **Patented July 17, 1917.**

Application filed May 17, 1917. Serial No. 169,346. Term of patent 3½ years.

To all whom it may concern:

Be it known that I, PHILIP E. BLUM, a citizen of the United States, residing at Dansville, in the county of Livingston, State of New York, have invented a new, original, and ornamental Design for Shoes, of which the following is a specification, reference being had to the accompanying drawing, forming part thereof, and wherein:

Figure 1 is a top plan view of the shoe embodying my design;

Fig. 2 is a side elevation thereof.

I claim:

The ornamental design for a shoe as shown.

PHILIP E. BLUM.

Witnesses:

SIMON N. ALBERT,

JOHN R. BLUM.
